(57) **CLAIM**

The ornamental design for a cable mounting bracket, as shown and described.

DESCRIPTION

FIG. 1 is a front perspective view of a cable mounting bracket in accordance with our design;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof;

FIG. 7 is a bottom plan view thereof;

FIG. 8 is a rear perspective view thereof; and,

FIG. 9 is a front perspective view the cable mounting bracket of FIG. 1 shown in a position of use with environmental subject matter.

The broken lines in the drawings depict portions of the cable mounting bracket that form no part of the claimed design. The additional broken lines in FIG. 9 depict environmental subject matter that forms no part of the claimed design.

1 Claim, 8 Drawing Sheets
